UNITED STATES PATENT OFFICE.

HUBERT HERMAN SEYL, OF CHICAGO, ILLINOIS.

METHOD OF AND MEANS FOR TREATING THE HAIR.

1,386,134.

Specification of Letters Patent.

Patented Aug. 2, 1921.

Application filed May 28, 1921. Serial No. 473,281.

To all whom it may concern:

Be it known that I, HUBERT H. SEYL, a citizen of the United States, residing at Chicago, in the county of Cook and State of Illinois, have invented certain new and useful Improvements in Methods of and Means for Treating the Hair, of which the following is a specification.

The invention relates to a method of and 10 means for treating the hair.

One of the objects of the invention is to provide a method of procedure and means for setting hair to remove kinks or curls therefrom, or to produce kinks, waves, or 15 curls therein.

Another object is to provide a method of and means by which a more or less permanency of set may be given to the hair by application of a material that serves as a 20 splint to hold or brace the individual hairs of wisps or locks of hair in the condition in which they have been placed during treatment and which does not injuriously burn, dry or split the hairs.

25 Other objects and advantages will readily appear.

In the drawings:—

Figure 1 shows one form of the device as it appears when used to remove kinks or 30 waves from the hair.

Fig. 2 shows the arrangement when it is desired to produce kinks or waves in the hair.

In both views the same reference characters are employed to indicate similar parts.

The tongs 5 are pivoted together at 6, and provided with handles 7 and 8. On the extended ends 9 and 10 may be secured rollers between which the hair is pressed. In Fig. 1 40 the rollers 11 and 12 are smooth faced, while in Fig. 2, the rollers 13 and 14 are corrugated. The rollers are interchangeable on the extended ends 9 and 10.

15 is a wick girdle or belt of absorbing material, such as a wick, that is to be contained between the rollers, as shown in the drawings. The belt 15 is saturated with a suitable fluid, such for example as a solution of gum tragacanth, or gum arabic, or 50 other similar suitable substance.

In treating kinky or wavy hair the instrument shown in Fig. 1 is employed. A wisp or lock of the hair is placed between the rollers 11 and 12, or directly between the 55 roller 11 and the upper surface of the wick or belt 15. The extreme unattached ends of

the hair are seized by the left hand of the operator and the instrument is moved back and forward along the lock of the hair, the belt or wick 15 moving in contact with the hair as the instrument is operated and imparting moisture to the lower surface of the wisp. The wick 15 is first saturated with the required solution and the rollers 11 and 12 are heated in any suitable manner 60 to a degree at which the liquid in the solution will be converted into steam. The liquid solvent or menstruum containing the stiffening substance will be deposited upon the hair from the wick, and the upper roller, 65 coming in contact with the hair will cause evolution of steam from the deposited liquid which will leave the more solid matter as a coating on the individual hairs of the wisp or lock. As the solid matter dries upon the 70 hair, the hair will become set or remain permanently in the condition in which it has been placed by the ironing smooth face rollers, so that any former wave or kink that may have been contained in the hair will 75 thereby be eliminated and the hair straightened, the deposited material serving as a means for holding each individual hair in the condition in which it has been placed by the operation of the instrument.

In the event that it is desirable to kink or wave straight hair the rollers 13 and 14 may be used and the wisp or lock of hair will be crimped or placed in undulating form between the teeth of the rollers, at the same 80 time the wick or girdle 15 will conform to the teeth and the interdental spaces of the rollers and the heat will contribute to temporarily hold the hair in the crimped condition, whereas the solid matter of the solution will have the same effect to hold the hair crimped as in the former case it maintains it straight.

Greater or less tension can be applied to the hair between the rollers by squeezing 100 the handles 7 and 8 together with more or less force.

Any sort of solution or mixture, well designed to set or splint the hair, may be used in the manner described by first saturating 105 the girdle, or wick 15, and placing the girdle over the lower roller of the pair, and then moving the instrument as a whole along the surfaces of a lock of the hair or of several strands thereof.

110 It has been found, by operation of the device, that the wick imparts the solution to

the surface of the hair and that the upper uncovered roller 11 or 13, as the case may be, coming in contact with the hair causes the liquid carrying the stiffening or setting substance to become evaporated, leaving the more material substance as a coating for the hair, and it is immaterial whether the hair be kinked or waved at the time that this operation is performed or whether the kinks or waves be taken from it, the material will 10 serve as means for holding the hair in the condition in which it has been placed by the operation of the machine.

While I have herein shown a single embodiment of my invention for the purpose of clear disclosure, it will be manifest to persons skilled in the art, that considerable variation may be made in the general arrangement and configuration of the parts 20 within the scope of the appended claims.

Having described my invention what I claim as new and desire to secure by Letters Patent, is:—

1. A method of treating hair which consists in simultaneously applying a suitable

solution on one side of a wisp or lock of hair and heat on the opposite side to evaporate the menstruum and to draw it through the wisp and to draw the solid matter of the solution into the wisp to coat the hair 30 therewith.

2. The method of treating hair which consists in applying pressure to a wisp of hair between two heated surfaces and simultaneously applying a suitable solution between one heated surface and the wisp whereby to evaporate the menstruum of the solution and to coat the hair of the wisp with the solid matter thereof until the solid matter sets, whereby to retain the hair in 40 condition in which it is placed by the treatment.

3. A device for treating hair comprising a pair of tongs having rollers on the respective prongs of the tongs and a liquid-absorbing girdle overlying one of the rollers.

In testimony whereof I hereunto subscribed my name.

HUBERT HERMAN SEYL, M. D.
